VEGETABLE AND FRUIT SIZING MACHINE

James R. Drummond, Onancock, Va.

Application October 31, 1933, Serial No. 696,100

1 Claim. (Cl. 209—102)

This invention relates to vegetable and fruit sizing machines and has for an important object thereof the provision of a machine which is adapted to size vegetables such as beans, peas or the like, before they have been removed from the pods.

Another object of this invention is to provide in a sizing machine of this type, means whereby the articles being sized are turned so as to be disposed lengthwise of the movement of the machine and the articles through the machine.

A further object of this invention is to provide in a machine of this type a plurality of belts which are spaced apart the desired distance and maintained in spaced relation so as to permit articles of undesired size to drop therebetween, the belts being so constructed as to gravitantly force the articles in the direction of the space between adjacent belts.

The above and various other objects and advantages of this invention will in part be described and in part be understood from the following detailed description of the present preferred embodiment, the same being illustrated in the accompanying drawings wherein:

Figure 1 is a longitudinal section partly in detail of a device constructed according to the preferred embodiment of this invention.

Figure 2 is an enlarged section taken on the line 2—2 of Figure 1.

Figure 3 is a fragmentary sectional view partly in detail taken on the line 3—3 of Figure 1.

Figure 4 is a fragmentary top plan of the device showing the staggered relation of the article straightening members supported by the frame.

Referring to the drawings wherein like numerals of reference designate corresponding parts throughout the several views, the numeral 10 designates generally a frame structure including end posts 11 and 12. The end posts 12 are connected together by means of a connecting member 13 and the end posts 11 are connected together by means of a connecting member 14. The end posts 11 and 12 are connected to each other by means of lower rails 15 and upper rails 16. A pair of rollers or drums 17 and 18 are rotatably supported in the frame 10 by means of bearings 19 and 20, respectively.

A plurality of endless belts or flexible members, generally designated as 21, are trained over these drums 17 and 18. The top run 22 of the belts 21 is preferably horizontally disposed and the lower run 23 is engaged by an idler drum or pulley 24 journaled between the upper bars 16.

A hopper or collecting pan 25 is secured to the frame 10 between the top run 22 and the lower run 23 and is preferably secured to side boards or members 26 carried by the frame 10 adjacent the top thereof. This collecting pan 25 is provided with a discharge neck 27 which may be engaged by a suitable carry-off means so that the material dropped into the hopper 25 may be removed in a suitable manner. The sides 26 of the frame 10 extend above the top run 22 of the belts 21, and a pair of transversely extending supporting bars 28 are supported between the sides 26 above the top run 22 of the belts 21.

A plurality of depending article alining or straightening members 29 in the form of elongated rods having V-shaped lower end portions 30 are secured between the bars 28 and overhang the top run 22 of the belts 21. The belts 21 are constructed with a flat lower side 31, a V-shaped upper or outer surface 32 and straight sides 33. The belts 21 are constructed with a V-shaped surface 32 for the purpose of causing the articles in the form of bean pods to gravitantly move toward the space between adjacent belts, and if the pods are smaller than the space between adjacent belts, the pods will fall through this space and into the hopper 25.

A second series of straightening members 34 are dependingly secured between a pair of transversely extending bars 35. The first series of straightening members 29 are spaced apart a distance whereby alternate runs of the belts 21 will be engaged thereby and the second series 34 of these straightening members is spaced apart a distance so as to engage the remaining of the belts 21 so that any pods or articles which are not straightened by the first series 29 will be straightened by the succeeding series 34.

In the present instance, these straightening members 29 and 34 are identical and are provided with a threaded upper end portion 36 and upper and lower nuts 37 and 38, respectively, engage above and below the bars 28 so as to securely hold the straightening members 29 in adjusted position. The straightening members 34 are similarly constructed.

A plurality of idling rollers 39 are rotatably supported between the side members 26 in a position to engage the underside of the belts 21 beneath the upper run 22. In this manner, the run 22 between the two drums 17 and 18 will be maintained straight.

A plurality of belt separating or spacing members 40, in the form of elongated rods 41, provided with threaded lower end portions engaged

by nuts 42, are supported by means of transversely extending bars 43 in a position to engage the upper and lower runs 22 and 23 of the belts 21 and maintain the belts 21 in the desired spaced relation one relative to the other. In the present instance, there are two of these spacing members 40 one adjacent the inner side of the drum 17 and the other adjacent the inner side of the drum 18. A platform 44 is supported above the top of the side members 26 by means of posts 45 and extensions 46 of the posts 11.

A power member in the form of a motor M is secured to the platform 44 and connected to the drum 17 by means of a flexible member 47 trained over wheels or sprockets 48 and 49. The sprocket 49 is mounted on the shaft 50 of the drum 17, and the sprocket 48 is mounted on a shaft 51 connected to a gear train or reducing means associated with the motor M. The motor M is here shown only diagrammatically, and it will be understood that any other form of power means may be used to drive the belts 21. A table 52 is disposed adjacent the intake side of the frame 10, and a conveyor means or belt 53 is disposed adjacent the opposite end of the frame 10 and is adapted to receive the articles in the form of bean pods or the like, which do not pass between the spaced belts 21.

In the use and operation of this device, the articles in the form of bean pods are disposed on a table 52 and forced in any desired manner onto the intake end of the upper run 22 of the belts 21. In the present instance, the belts 21 rotate in a manner whereby the upper run 22 moves in the direction from the end 12 to the end 11. Initially, the bean pods are positioned on the belts 21 in a more or less jumbled fashion, that is, a number of the pods will extend crosswise of the belts 21, while others will be disposed lengthwise of the belts and by reason of the V-shaped upper portion 32 of these belts 31, the smaller or thinner of the pods will drop between adjacent belts and into the hopper 25. The pods which are disposed transverse to the length of the belts 21 will be at least partially turned by engagement with the first series of straightening members 29, and if they are not entirely straightened so as to be disposed in a direction parallel with the movement of the belts 21, the second series 34 of these straightening members will straighten the pods

and the pods will be maintained in edgewise or substantially upright position between the adjacent belts by reason of the V-shaped upper side of the belts 21. Any pods which are too thick to pass between the adjacent belts 21 will be carried along until the end 11 is reached, whereupon these relatively large pods will be dropped onto the conveyor belt 53 and conveyed to any desired source. The pods culled out and dropping into the hopper 25 may be removed through the discharge neck 27. The posts 12 are provided at spaced intervals with openings 54, through which bolts or bars may be passed and the upper frame bar 16 lowered or raised to the desired point with the opposite end which is engaged with the end posts 11 as a fulcrum. In this manner, the belts 21 can be loosened or tightened to the desired degree as the raising or lowering of the bars 16 will raise or lower the idler drum 24.

It is, of course, understood that various changes and modifications may be made in the details of construction and design of the above specifically described embodiment of this invention without departing from the spirit thereof, such changes and modifications being restricted only by the scope of the following claim.

What is claimed is:—

A sizing machine comprising a frame, a plurality of V-shaped sizing belts disposed in the frame in spaced relation to each other, means engaging one flat face of the belts to support the belts for movement in the frame, one run of said belts being substantially horizontal, means engaging the other run of the belts to maintain the belts in tight relation, means engaging said one run of the belts to maintain said one run in substantially horizontal position, means for holding the belts in spaced relation to each other, a plurality of article straightening members, means for supporting said members in dependent relation above alternate belts, said members having a V-shaped notch in the lower ends thereof confronting the V-shaped upper surface of the belts and coacting with said means for holding the belts in spaced relation to each other to hold the belts against lateral movement one relative to the other while turning elongated articles on the belts in a position lengthwise of the belts.

JAMES R. DRUMMOND.
